(57) **CLAIM**

The ornamental design for a cane handle, as shown and described.

DESCRIPTION

FIG. 1 is a front perspective view of a cane handle, showing my new design;

FIG. 2 is a rear perspective view thereof;

FIG. 3 is a front elevational view, the rear elevational view being a mirror image of FIG. 3;

FIG. 4 is a left side view thereof;

FIG. 5 is a right side view thereof;

FIG. 6 is a top plan view thereof; and,

FIG. 7 is a bottom plan view thereof.

The broken lines in the figures are for the purposes of illustrating portions of the cane handle, which form no part of the claimed design.
